Primary Examiner—Alan P. Douglas*Assistant Examiner*—Robert M. Spear*Attorney, Agent, or Firm*—Terry M. Germstein[57] **CLAIM**

The ornamental design for a container cover with counting and display means, as shown and described.

DESCRIPTION

FIG. 1 is a front, top and side perspective view of the container cover with counting and display means showing our new design;

FIG. 2 is a front elevational view thereof;

FIG. 3 is a rear elevational view thereof;

FIG. 4 is an end elevational view thereof, the end opposite being a mirror image of the end shown in FIG. 4;

FIG. 5 is a top plan view thereof;

FIG. 6 is a bottom plan view thereof; and,

FIG. 7 is a perspective view thereof.
